ATTORNEY

UNITED STATES PATENT OFFICE.

GEORGE H. SHELLABERGER, OF MOUNT VERNON, OHIO.

MACHINE FOR MAKING FENCES.

SPECIFICATION forming part of Letters Patent No. 300,517, dated June 17, 1884.

Application filed April 2, 1884. (No model.)

To all whom it may concern:

Be it known that I, GEORGE H. SHELLABERGER, a citizen of the United States, residing at Mount Vernon, in the county of Knox and State of Ohio, have invented a certain new and useful Improvement in Machines for Manufacturing Fences; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

15 My invention relates to improvements in a machine for manufacturing picket fencing by interweaving palings into strands of wire, and a device connected therewith to guide a longitudinal wire while the same is being interlaced with the palings and attached to the upper and lower strands to stiffen the panels.

The mechanism is illustrated in the accompanying drawings, in which Figure I is a plan view of the machine. Fig. II is a side elevation of the same. Fig. III is a front view of the depressing-board.

Similar letters refer to similar parts throughout the several views.

A is the frame, which consists of side rails, 30 cross-pieces, and legs to hold the operating mechanism at a suitable altitude. On the cross-bar R, near the rear end of the frame, is supported the spool J, on which is wound a single wire, h. The rods m are supported on 35 posts V and W of the frame, and these rods give support to the guide n. This guide has a hole in one end for the wire to pass through, and the other end has a slot to embrace the rod, on which it is secured by a pin or bolt.

40 I is a roller having bearings in posts of the frame near the front end of the same. The wire to be interlaced diagonally with the slats is carried from the spool J, passed through the guide, thence over the roller I, thence to the outer strand of the palings, where it is twisted onto the same. For the purpose of interlacing said wire a depressing device is used, which consists of a notched board, (see Fig. 3,) 45 which is attached to arms and pivoted to posts 50 of the frame. The notches are spaces for the

strands, so that the lower face of the board may pass beneath the strands, and thereby carry the wire alternately beneath the slats; and thus the wire, which is held in diagonal position, is interlaced with the palings. In 55 the process, when the outer strand is reached, the wire is twisted about the said strand, and the guide n is shifted to the opposite rod. The guide, when placed, is held fixedly to the wire, which traverses the rod as the wire enters into 60 the structure.

The machine, as illustrated in plan, is for the construction of a paling with five strands of wire, the outsides of which are alone exhibited.

65 B are a series of shafts supported in bearings on cross-pieces of the frame. To the front end of said shafts are attached cranks o, and the cranks are connected by their pins to the bar D, the central pin being elongated to be 70 grasped by the hand in turning the machine. To the rear end of the shafts are attached spool-frames, the use of which being to hold the spools x, on which are wound, side by side, two wires, and to direct the wires in close 75 proximity to the slats as they are being interwoven into the panels, said wires passing through orifices in the rear of their frames.

80 The operation is thus: The spool-frame being in vertical position, the slat is thrust between the wires, the shafts are given one or two turns, and another slat is placed in position, and the process continued. At the entrance of every second slat the depressing device is lowered, thus carrying the diagonal wire beneath, thereby interlacing the slats by placing the wire alternately above and below them.

85 At the rear end of the frame is a well-known device for the purpose of winding up the structure as the manufacturing progresses.

90 K is the shaft on which the structure is wound. The wires constituting the strands are attached to said shaft in any convenient manner.

95 L is a ratchet-wheel attached to the spindle of the shaft, and s is a pawl pivoted to the frame. The arm t carries a pawl, s', which is backed by a flat spring, and this arm is jointed to the foot-lever v by the connection u. By pressing down upon this lever the shaft is 100

caused to partially rotate, and the fixed pawl prevents any return movement.

Having fully described my invention, what I desire to secure by Letters Patent is—

5 1. In a machine for manufacturing fence, the depressing device to carry down the diagonal wire to interlace the same into the panel, consisting of a notched board suspended by pivotal arms from the frame, substantially as set forth.

10 2. The combination of the roller I, rods m,

guide n, and bar R, carrying a spool to give position to a diagonal wire, substantially as described.

In testimony that I claim the foregoing as 15 my own I affix my signature in presence of two witnesses.

GEORGE H. SHELLABERGER.
